UNITED STATES PATENT OFFICE.

MARGARET ALICE YORK, OF NEW YORK, N. Y.

DESIGN FOR A CHILD'S COSTUMER.

Application filed November 22, 1921. Serial No. 517,111. Term of patent 3½ years.

To all whom it may concern:

Be it known that I, MARGARET ALICE YORK, a citizen of the United States, and a resident of the city of New York, borough of Manhattan, in the county and State of New York, have invented a new, original, and ornamental Design for a Children's Costumer, of which the following is a specification, reference being had to the accompanying drawing, forming part thereof.

In the accompanying drawing:

I claim:

The ornamental design for a child's costumer, as shown.

MARGARET ALICE YORK.
